UNITED STATES PATENT OFFICE.

HORACE P. CARVER, OF NEBRASKA CITY, NEBRASKA, ASSIGNOR TO
CARVER, SPRAGUE & CO., OF RACINE, WISCONSIN.

DESIGN FOR A SAD-IRON.

SPECIFICATION forming part of Design No. 17,642, dated August 23, 1887.

Application filed May 17, 1887. Serial No. 238,561. Term of patent 14 years.

To all whom it may concern:

Be it known that I, HORACE P. CARVER, a citizen of the United States, residing at Nebraska City, in the county of Otoe and State of Nebraska, have invented and produced a new and original Design for Sad-Irons; and I do declare the following to be a full, clear, and exact description of the same, reference being had to the accompanying drawings, forming a part thereof.

My invention consists in a design for a sad-iron, and it is fully disclosed in the following specification and claims.

In the drawings, Figure 1 is a view of the iron, showing the particular shape of the peripheral surface. Fig. 2 is a perspective view of the iron, showing the recesses in the face of the projection on the side of the same.

In said figures of the drawings, A is the body of the sad-iron, and B the handle. The sad-iron body has two parallel smoothing faces or sides, while the edges are similar but reversely curved cylindric surfaces, causing the smoothing faces to take the form of elongated ellipses with pointed ends. One edge is provided with a projecting surface, *a*, which is also curved, but has its curvature differing from the curvature of the edge, the same being a section of a cylindric surface having a greater diameter than that of the edges of the iron. This surface is provided with numerous small recesses, as shown.

The handle B of the iron is curved in the form of a section of a circle.

The curves of the side of the iron and handle are not of equal circles and are not concentric. The ends of the handles are provided with enlargements having inner faces fitting against and being equal in area to the outer ends of the cylindrical projections, and either forming cylindrical extensions of the projections, as shown at *b'*, or forming conoidal extensions thereof, as shown at *b''*.

What I claim, and desire to secure by Letters Patent, is—

1. In a design for a sad-iron, the design of the body of the same, consisting of two flat parallel sides and two equally but reversely curved edges, one of said edges being provided with a slight projection the surface of which is curved and recessed, substantially as described and shown.

2. In a design for a sad-iron, the design of the body of the same, consisting of two flat parallel sides and two equally but reversely curved edges meeting at a point at each end, one of said sides having a projection provided with a curved surface, the said surface being of different curvature from the edge of the iron from which it projects, substantially as described and shown.

3. The design for a sad iron, which consists of an iron-body having equally but oppositely curved edges and a curved handle, the curves of the handle and the edges of the iron-body being sections of different and eccentric circles, the ends of the handle extending beyond the ends of the iron-body and springing therefrom, substantially as described.

4. The design for a sad-iron, which consists of a body having equally but reversely curved edges, and provided at its ends with cylindrical projections whose axis is in line with the central longitudinal axis of the body, and a curved handle having enlargements forming extensions of said projections, substantially as described and shown.

In testimony whereof I affix my signature in presence of two witnesses.

HORACE P. CARVER.
